UNITED STATES PATENT OFFICE.

JOHN M. FEDDERS, OF BUFFALO, NEW YORK, ASSIGNOR TO FEDDERS MANUFACTURING COMPANY, INC., OF BUFFALO, NEW YORK, A CORPORATION OF NEW YORK.

RADIATOR.

1,297,454.

Specification of Letters Patent. Patented Mar. 18, 1919.

Application filed March 11, 1918. Serial No. 221,628.

To all whom it may concern:

Be it known that I, JOHN M. FEDDERS, a citizen of the United States, residing in Buffalo, in the county of Erie and State of New York, have invented new and useful Improvements in Radiators, of which the following is a specification.

This invention relates to that type of radiators for use in cooling the water of explosion engines in which a plurality of tubes are employed through which the air passes and which are arranged side by side so as to form water channels or conduits between the adjacent outer sides of these tubes.

15 The object of this invention is to provide improved means for increasing the abstraction of the heat of the water from inner sides of these tubes to the atmosphere, which means are capable of being produced at low 20 cost and easily assembled with the tubes and which not only materially increase the efficiency of the radiator but also improve the appearance of the same.

In the accompanying drawings:

25 Figure 1 is a fragmentary front elevation, partly in section, of a radiator core having its air tubes equipped with my improved radiating means. Fig. 2 is a transverse section taken on line 2—2, Fig. 1. Fig. 3 is a 30 perspective view of one section of a radiating member arranged in one of the air tubes and constructed in accordance with my improvements.

Similar characters of reference indicate 35 corresponding parts throughout the several views.

Although the core of the radiator adapted 40 to receive my improved radiating means may be variously constructed, the same as shown in the drawings comprises a plurality of sheet metal tubes which are arranged side by side, each of these tubes being preferably of hexagonal form in cross section and having its opposite ends 1, 1, enlarged while its 45 central part 2 intermediate of its ends is reduced in diameter. In the assembled position of these tubes the facets on the enlarged ends of each tube engage with the corresponding facets of adjacent tubes while the 50 intermediate parts of adjacent tubes are separated from each other and form tortuous water conduits or channels 3 between adjacent tubes. The water is circulated through these water channels or conduits from one 55 end thereof to the other in any suitable man-

ner and the cooling of the same is effected by the flow of air through the air tubes in the usual and well known manner.

In order to increase the radiation of heat from the inner sides of the air tubes to the 60 atmosphere each of these tubes is provided with an internal radiating member which embodies my invention.

In its general construction this improved radiating member comprises a plurality of 65 longitudinal plaits which are arranged in an annular row and engage their outer edges with the inner corners of the bore or the inner side of the respective air tube whereby the radiating member is held against turning in the tube and these parts are held in their proper position circumferentially relatively to each other. In its preferred form this radiating member is divided diametrically and lengthwise into two sections each 70 of which is constructed of a strip of metal which is corrugated or bent so as to form two whole plaits which are arranged side by side and two half plaits which are arranged on the outer sides of the whole plaits, 80 as shown in Fig. 3. The plies 4, 4, of each whole plait are connected with each other at their outer edges but the outer edge of each half plait 5 engages with the outer edge of the adjacent half plait of the companion 85 radiator section so as to form a whole plait therewith, as shown in Fig. 1. The plies of each plait are separated from each other inwardly from their outer edges so that each 90 ply serves to individually carry away heat from the inner side of the air tube and thereby utilize both of its sides for this purpose, so as to obtain the maximum radiating efficiency for the amount of metal used. The inner edge of each ply of one plait is connected by a circumferential web 6 with the inner edge of one ply of an adjacent plait and each of these webs is separated or spaced from the web on the diametrically opposite 95 sides of the radiating member and is preferably curved concentrically with the axis of the respective air tubes so that the several webs of a radiating member approximately form a tube.

The end portions of the outer edges of the 100 plies of each plait project laterally outward as shown at 7 and these projecting portions engage with the inner sides of the enlarged end portions of the respective air tube while the central part of the outer edge of each 110

ply intermediate of the end portions thereof recede inwardly relative to the companion end portions, as shown at 8, and engage with the contracted central or intermediate part of the respective tube. By this means inwardly facing shoulders 9 are formed on the plies of the plaits between the projecting end portions and the receding central parts thereof which shoulders engage with 10 the outwardly facing shoulder 10 formed in the bore of the respective air tube between the enlarged end portions and the contracted central part thereof, whereby the radiating member is prevented from moving lengthwise in the tube and is thereby held against displacement.

The projecting and receding portions on the outer edges of the several plaits of the radiating member are preferably formed by 20 extending the end portions of the whole plaits of each section laterally outward the full width of the plies so as to form the extensions 7 but removing or cutting away the central part of the outer edges of a pair of 25 plies forming a whole plait so that the intermediate parts 8 thereof are disconnected from each other at their outer edges and recede relative to the companion end portions of these plies, as best shown in Figs. 2 and 3. 30 The outer edge of the plies forming one-half of a plait on each radiating section have the end portions 7 of their outer longitudinal edges projecting laterally while their intermediate parts are cut back to form the receding central parts 8 thereof so that when each 35 of these half plies is assembled with a companion half ply of another section these two plies together form a whole plait which has substantially the same form as one of the 40 whole plaits in which the two plies are integrally connected at their outer edges.

When placing this radiating member in an air tube the sections are contracted sufficiently to permit one enlarged end thereof to 45 pass through the contracted central part of the air tube and after these sections have been slipped into the tube far enough to bring their opposite ends into alinement these sections are again permitted to expand 50 so as to engage the enlarged end portions of the radiating member with the enlarged ends of the tube and the contracted central parts of this member with the central part of the tube. This expansion of the radiating member is possible owing to the resilient or 55 springlike character which this member possesses due to its form.

After the several tubes and the radiating members therein have been thus assembled 60 the opposite ends of these parts are dipped in solder so that the several tubes are connected with each other at their ends and form a water tight joint therebetween and the opposite ends of the sections of each radiating member are connected with each

other and with the companion tube so as to further hold these parts against displacement.

In its completed form this radiator not only possesses greater rigidity and radiating 70 efficiency but the same also presents a very neat and attractive appearance.

I claim as my invention:

1. A radiator comprising a plurality of tubes arranged side by side and each tube 75 having enlarged ends which engage with the enlarged ends of adjacent tubes and having its intermediate part reduced whereby the same is spaced from the reduced intermediate parts of adjacent tubes and forms passages between the several tubes, and radiating members arranged in each tube comprising a sheet of metal which is corrugated to form a plurality of longitudinal plaits the outer edges of the plies of some plaits being 80 connected with each other and the inner edge of each ply of one plait being connected with the inner edge of a ply of an adjacent plait, the outer edges of the plies of each plait having their end portions projecting 85 laterally into engagement with the enlarged ends of the respective tube and the intermediate outer edge portions of the plies of each plait receding inwardly relative to the companion end portions and engaging with the 90 contracted part of the respective tube.

2. A radiator comprising a plurality of tubes arranged side by side and each tube having enlarged ends which engage with the enlarged ends of adjacent tubes and having 100 its intermediate part reduced whereby the same is spaced from the reduced intermediate parts of adjacent tubes and forms passages between the several tubes, and radiating members arranged in each tube comprising a sheet of metal which is corrugated to form a plurality of longitudinal plaits the outer edges of the plies of some plaits being 105 connected with each other and the inner edge of each ply of one plait being connected with the inner edge of a ply of an adjacent plait, the outer edges of the plies of some plaits having their end portions connected and projecting laterally into engagement with the enlarged ends of the respective tube while 110 the intermediate parts of the outer edge portions of said plaits are disconnected from each other and recede relatively to the companion end portions and engage with the contracted intermediate part of the respective tube.

3. A radiator comprising a plurality of tubes arranged side by side and each tube having enlarged ends which engage with the enlarged ends of adjacent tubes and having 125 its intermediate part reduced whereby the same is spaced from the reduced intermediate parts of adjacent tubes and forms passages between the several tubes, and radiating members arranged in each tube comprising 130

ing a sheet of metal which is corrugated to form a plurality of longitudinal plaits the outer edges of the plies of some plaits being connected with each other and the inner edge 5 of each ply of one plait being connected with the inner edge of a ply of an adjacent plait, said radiating member being divided lengthwise into a plurality of sections each of

which contains a whole plait which has its two plies connected at their outer edges and 10 their inner edges disconnected and two half plaits each of which has its inner edge connected with a ply of an adjacent plait while its outer edge engages with a ply forming a half plait of another section.

JOHN M. FEEDERS.
